Primary Examiner — Susan M Lee

(74) Attorney, Agent, or Firm — Gardere Wynne Sewell, LLP

(57) CLAIM

The ornamental design for a deer cleaning cart, as shown and described.

DESCRIPTION

FIG. 1 is a perspective view of a deer cleaning cart according to my new design;

FIG. 2 is a left side elevation view of the deer cleaning cart shown in FIG. 1;

FIG. 3 is a right side elevation view of the deer cleaning cart shown in FIG. 1;

FIG. 4 is a front elevation view of the deer cleaning cart shown in FIG. 1;

FIG. 5 is a rear elevation view of the deer cleaning cart shown in FIG. 1;

FIG. 6 is a top plan view of the deer cleaning cart shown in FIG. 1; and,

FIG. 7 is a bottom plan view of the deer cleaning cart shown in FIG. 1.

The broken lines are for illustrative purposes only and form no part of the claimed design.
